UNITED STATES PATENT OFFICE.

CHARLES ALLEN MAGNE, OF HALDANE, ILLINOIS.

CAR-COUPING.

SPECIFICATION forming part of Letters Patent No. 442,193, dated December 9, 1890.

Application filed May 6, 1890. Serial No. 350,788. (No model.)

To all whom it may concern:

Be it known that I, CHARLES ALLEN MAGNE, a citizen of the United States, residing at Haldane, in the county of Ogle and State of Illinois, have invented certain new and useful Improvements in Car-Couplings; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention has reference to improvements in car-couplings; and the object of my invention is to afford means for automatically coupling the cars, and also to permit the same to be uncoupled from either the side or the top of the car, and thereby avoid any necessity for the operator going between the cars either to couple or uncouple; also, to suspend the automatic coupling at such times as it is desired to bring the cars into contact without effecting a coupling.

The means for effecting the above objects are exhibited in the drawings, in which—

Figure 1 is a top view of the lower portion of a car provided with my invention, the floor of the car being cut away to exhibit the same. Fig. 2 is a longitudinal vertical section of the lower portion of a car provided with my invention. Fig. 3 is a view of a portion of the front of the bottom of a car provided with my invention. Fig. 4 is a view of a portion of the end of the bottom of a car, exhibiting the mode of seating my invention therein.

As my invention is intended to be applied at each end of the car and the device is the same at each end, and such device is adapted to be attached to any of the usual forms of cars, I do not deem it necessary to show or describe the car proper any further than is requisite to a clear understanding of the mode of attachment, character, and operation of my invention.

A is the frame of the car, consisting of the front cross-plate A' and the usual side plates A².

B B are longitudinal intermediate beams to afford additional support to the floor C of the car.

D D are short longitudinal beams suitably bolted to the under side of the beams B or otherwise suitably attached to the under side of the frame of the car. The beams D project slightly beyond the end of the car, and in the inner walls of said beams D, a suitable distance from the inner ends thereof, are formed vertical recesses 1.

A coupling and draw-bar E, hereinafter described, is removably placed in the interval between the beams D and held in place by the recess 1 aforesaid and short cross-plates F F, suitably bolted to the lower and after sides of the beams D. The draw-bar E consists of an upper plate 2 and a lower plate 3, suitably bolted together, with the interval 4 between them. On the outer end of the plates 2 and 3 is formed the draw-head G, having a central draw-pin hole 5 and auxiliary or additional end pin-holes 6 6, the latter being intended merely to afford means for using the ordinary link-coupling when such use is desirable either as auxiliary to the central coupling or in case of temporary injury to the latter.

Between the plates 2 and 3, at the inner ends of the latter, there is loosely seated a cross-plate 7, provided with the central hole 8, through which there is inserted a suitable draw-pin H, provided with the head 9. The draw-pin H is provided with peripheral threads 10 at its forward end, which are screwed into a longitudinal socket 11, formed in the sliding block J. The block J is inserted lengthwise in a suitable opening G', formed centrally in the draw-head G, and extends inwardly between the plates 2 and 3, and is held in place by the draw-pin H being screwed into the inner end of said block J, the head 9 on said pin preventing the latter from passing outward farther than to the point where said head abuts against the inner side of the cross-plate 7.

K is a rear cross-plate, and L the front cross-plate, loosely sleeved centrally on the draw-pin H, near the inner end of the latter, transversely between the plates 2 and 3, a short distance apart. The coiled spring M is seated on the draw-pin H between the plates K and L. The upright bolts 12, which hold the plates 2 and 3, serve as stops against the

forward movement of the plate L, and the rear similar bolts 13 limit the rear movement of the plates 7 and K. On the draw-pin H, between the plate L and block J, there is seated a coiled spring 14. The inner end of the block J is preferably formed hollow for a short distance to permit the use of as long a spring 14 as practicable. The front end of the block J (which when the front end of the draw-pin H is screwed into the inner end thereof forms substantially a prolongation of the latter) is also formed hollow, consisting of an upper surface 15 and downwardly-depend ing flanges or sides 16 integral therewith.

15 A link-receiving and guide plate N, having a flat bottom 17 and triangular-shaped sides 18, is suitably attached at its inner end by a horizontal transverse pivot 19, which passes through the sides 18 thereof and the sides 16 of the block J. The formation, location, and seating of the guide N are such that when the block J, by means of the springs M and 14, is suitably projected beyond head G to its outward limit, which is when the head 9 engages the plate 7, the guide N drops down at its outer end, so as to present on its bottom 17 an inclined surface for the reception of the coupling-link, and as by the momentum of the cars the block J is forced back in the draw-head G (the springs M and 14 yielding for that purpose) the lower side of the opening G' in said draw-head forces the carrier or guide N upward within the sides 16 of the block J. The opening G' being of about the depth of the sides 16, the withdrawal aforesaid of the block J carries the movable guide N upward, and the latter in turn carries the link within said draw-head in position for engagement with the coupling-pin through the central pin-hole 5 therein.

20 O is the coupling-pin, which is provided with the rearwardly-extending head 20, in which is formed a horizontal slot 21. To the front cross-plate A' is pivoted in a horizontal position an oscillating rod P, which extends from about the center of the car to near the outer edge thereof, and its outer end is provided with the handle 22 and at its inner end with a downwardly-projecting arm 23, adapted to be inserted through the slot 21 in the head of the pin O. The arm 23 at its inner end has three bends—first 24, from the car, perpendicular therewith, then at right angles laterally 25, and then at a right angle upwardly 26. When inserted in the slot 21, the head 20 of the pin O rests upon the lateral or second bend 25, and the upward projection 26 is simply to prevent the pin from shaking from the rod P. The pin O is inserted in the pin-hole 5 of the draw-head G. When the coupling is effected, the pin O drops into place through the coupling-link by its own gravity, the lower end of said pin having previously rested on the upper surface 15 of the block J inwardly from the pin-hole 27 therein. A corresponding pin-hole 30 is formed in the link-receiver N, and as the part J by the mo-

mentum of the cars is pushed inwardly the holes 27 and 30 are moved directly under the pin-hole 5 in the head G, when the pin O drops downward of its own gravity through all of said holes and the coupling-link. The pin O is withdrawn for coupling by means of handle 22 on the rod P without the operator passing down between the cars. This handle 75 is slightly within the edge of the car, so as to be out of danger of casual engagement, but so near the end that it can be reached without danger or exposure.

The limit of oscillation of the rod P is gaged 80 by a stop R, which consists of a short arm integral with the rod P, which, when the pin O is drawn sufficiently to clear the lower end of said pin from the coupling-link and the pin-hole 27 in block J, abuts against the plate A' 85 and prevents the further removal of the pin O, allowing the lower end of the latter to rest in the hole 5 in the draw-head G and upon the upper surface 15 of the part J, as aforesaid. The arm R is further utilized in the case of 90 box-cars to attach a chain thereto, which can be raised by any suitable device on the top of the car, and the uncoupling thereby be effected from the latter position. The moment that the rod P lifts the pin O out of engagement with the hole 27 in the upper surface of the block J the spring 14 throws the block J outwardly, carrying the pin-hole 27 beyond head G, thereby forming a seat on block J for the lower end of said pin O.

100 There are occasions, such as switching in the yards or in changing cars, when a coupling is not desired, though the cars may come in contact.

To keep the coupling-pin from dropping 105 into engagement every time the block J is driven in by the impacts of the cars, I provide a slide S, which is seated on the outer face of the plate A' by means of bolts 28, passed through horizontal longitudinal slots 110 29 in the said plate, and said slide thereby is adapted to be moved out under the handle 22 of the rod P and thereby temporarily suspend the pin O and the automatic character of said coupling until such time as the 115 coupling is required, when said slide can be pushed inward out of engagement with the handle 22 and rod P have its normal action.

The operation of my invention is as follows: The coupling-link is placed in position 120 in one car, so that the pin O of the opposite car may engage the same, and in this situation the link projects beyond the end of the part J, with its outer end slightly depressed. In the car in which the operation of coupling 125 is to take place the coupling-pin O is supported by its lower end resting upon the top of the part J, the latter projecting, as shown in Fig. 2, being thrown out by the joint expansion of the springs M and 14. As the cars 130 come in contact the projecting end of the link is caught upon the upper surface of the bottom of the opposite guide N, and the further mutual approach of the cars forces the block.

J inward (said springs M and 14 yielding for that purpose) until the hole 27 in block J registers with the hole 5 in the draw-head G, when the pin O drops through part J and the coupling-link carried within the latter. The parts are so proportioned that the link enters the projecting portion of J beyond the hole 27 in the latter before the withdrawal mentioned of block J begins. Therefore when the coupling-pin O drops through the opening 27 in block J it also passes through the interior of the link. The link guide and carrier N in the withdrawal aforesaid of the block J is carried up by the conformation of the opening G' of the draw-head G into a horizontal position, as shown in Fig. 4. In this position the draft is not upon the block J, but wholly upon the draw-head G. The uncoupling is effected, as aforesaid, by the means of the rod P, either through the handle 22 from the ground or by means of a chain attached to the arm R from the top of the car. A sufficient elasticity is afforded for starting the car by the rear spring M on the pin H, the front plate L forming the stationary head, the latter being held by the bolts 12. The concussions from the impacts of the cars is relieved by both the springs M and 14, the rear plate K in such situation becoming stationary and being supported against the rear pins 13.

The advantages which I claim for my invention are that there is afforded thereby a device which couples automatically and can be uncoupled without the interposition of the body between the cars. The drooping character of the link guide and carrier N adapts the coupling to cars of different altitudes. The use of both springs M and 14 in the impact of the cars affords a double cushion against the results of concussion. In flat cars all of the apparatus, when the pin O is in position, is below the plane of the floor of the car, so as to form no obstacle in moving from one car to the other and no obstruction to the usual unloading of gravel by plows, common on construction-trains; also, by the means of the slide S the automatic character of the coupling may be suspended at such times when the coupling is not desired; also, my invention can be used in connection with cars provided only with the ordinary link-and-pin coupling. The oscillating rod P, as a means of controlling the vertical movement of the pin O, has the advantage in moving a measured distance, which is not true with links or ropes, which are liable to become kinked or knotted. The engaging end of the rod P, in the oscillations of the latter, traverses the slot 21 in pin O, so that said pin is lifted and held in a substantially-vertical position.

What I claim as my invention, and desire to secure by Letters Patent of the United States, is—

1. In a car-coupling, the combination of the

beams D D, suitably attached to the body of the car and provided, respectively, with recesses 1 1, the draw-head G, provided with central-pin hole 5, draw-pin H, sliding block J, plates K and L, sleeved on pin H and adapted to project, respectively, within said recesses 1, and rear spring M, said drawing mechanism being suitably supported between the beams D D, substantially as shown, and for the purpose described. 75

2. In a car-coupling, the combination of the beams D D, suitably attached to the frame of the car and provided, respectively, with recesses 1, the draw-bar E, the draw-pin H, the plates K and L, sleeved on said pin H and extended within the said recesses 1, supporting cross-plates F F, the sliding block J, adjustably attached to draw-pin H and provided with pin-hole 27, the link receiver and guide N, provided with hole 30 and pivotally attached to the part J, spring 14, coupling-pin O, provided with slot 21, and coupling-rod P, adapted at one end to engage said coupling-pin within said slot and provided with the handle 22, substantially as shown, and for the purpose described. 85

3. In a car-coupling, the combination of the beams D D, suitably attached to the frame of the car and provided, respectively, with recesses 1, the draw-bar E, provided with head G, having hole 5, the draw-pin H, plates K and L, sleeved on said pin and extended within the said recesses 1, supporting cross-plates F F, the sliding block J, adjustably attached to draw-pin H and provided with pin-hole 27, the link receiver and guide N, provided with hole 30 and pivotally attached to the block J, spring 14, coupling-pin O, provided with slot 21, coupling-rod P, adapted at one end to engage said coupling-pin within said slot and provided with handle 22, and stop-arm R, substantially as shown, and for the purpose described. 95

4. In a car-coupling, the combination of the beams D D, suitably attached to the frame of the car and provided, respectively, with recesses 1, the draw-bar E, provided with head G, the pin H, plates K and L, sleeved on said pin and extended within the said recesses 1, supporting cross-plates F F, the block J, adjustably attached to draw-pin H and provided with pin-hole 27, the link receiver and guide N, provided with hole 30 and pivotally attached to the block J, spring 14, coupling-pin O, provided with slot 21, uncoupling-rod P, adapted at one end to engage said coupling-pin within said slot and provided with handle 22, the stop-arm R, and slide S, substantially as shown, and for the purpose described. 110 115 120 125

5. In a car-coupling, the draw-bar E, adjustably connected at its inner end to the body of the car and provided at its forward end with the draw-head G, having the central longitudinal opening G' and vertical pin-holes 5, the sliding block J, loosely sleeved within 130

said draw-bar and provided with pin-hole 27, the link-guide N, pivotally attached at its inner end to the block J, the spring 14, draw-pin H, coupling-pin O, provided with the slot

5 21, and the rod P, adapted to engage said pin and raise it a limited distance only, substantially as shown, and for the purpose described.

In testimony whereof I affix my signature in presence of two witnesses.

CHARLES ALLEN MAGNE.
